UNITED STATES PATENT OFFICE.

EMIL EITEL, OF CHICAGO, ILLINOIS.

DESIGN FOR AN OBSERVATORY.

SPECIFICATION forming part of Design No. 20,529, dated February 24, 1891.

Application filed January 14, 1891. Serial No. 377,777. Term of patent 3½ years.

To all whom it may concern:

Be it known that I, EMIL EITEL, a subject of the Emperor of Germany, residing at Chicago, in the county of Cook and State of Illinois, have invented a new and useful Improvement in a Design for an Observatory, of which the following is a specification.

My design relates to the class of observatory represented by the well-known Eiffel Tower; and my object is to provide such an observatory in a novel and attractive design.

In the accompanying drawing my design is represented in broken elevation in the form of a mountain or hill.

The structure in the representation illustrating my design is an observatory in the form of a mountain, and the illustration thereof is broken to show that it is hollow, as

it essentially is to adapt the structure for the purpose of the design.

The leading feature of my design is a mountain or hill representation. At the summit of the mountain is a suitable ornamental structure, shown as a castle, the more effectively to set off the design besides serving for observatory purposes.

What I claim is—

The design for an observatory herein shown and described, the same consisting in a structural representation of a mountain surmounted by an ornamental structure, such as a castle, as set forth.

EMIL EITEL.

In presence of—
J. W. DYRENFORTH,
M. J. FROST.
